J. SCHMITT
CARDING MACHINE

Filed Aug. 5, 1926

Inventor:
Joseph Schmitt
per: J. Schmitt
Attorney.

UNITED STATES PATENT OFFICE.

JOSEPH SCHMITT, OF BRUNSTATT, FRANCE.

CARDING MACHINE.

Application filed August 5, 1926, Serial No. 127,440, and in France August 19, 1925.

The present invention relates to an improvement in cotton carding machines, the said improvement residing therein, that carding bars, which are movably supported, are provided under the breaker cylinder in such a manner that they are normally in carding or working position, but are intermittently at regular intervals brought to a cleaning position, so that any flocks which may be adhering may be removed.

The object of the invention is to attain a greater efficiency of the breaker cylinder, resulting from the fact that the flocks are better spread, divided and carded than has been the case heretofore, and that they reach the large cylinder better freed from fibre than with an ordinary breaker. The well divided flocks no more tend to clog the large cylinder, so that a product better carded than heretofore may be obtained.

Two embodiments of the invention are, by way of example only, illustrated by the accompanying drawing, wherein:

Figs. 1 and 2 are respectively an elevation and a side view of one form of the device according to the invention applied to the breaker cylinder of a carding machine; and

Fig. 3 is an elevation showing a portion of a breaker cylinder, with a modified form of the device according to the invention applied thereto.

Referring to the said drawing, *a* indicates the large cylinder, *b* indicates the breaker cylinder and *c* indicates the feeder. In the space between the breaker bars *d* under the breaker cylinder *b* are arranged carding bars such as *e*, *e*₁, *e*₂, *e*₃. These carding bars *e* are provided with teeth *f* as shown in Fig. 2. In the position shown in full lines in Fig. 1, the carding bars *e*, *e*₁, *e*₂, *e*₃ are in carding or working position, in which they spread and divide the flocks and remove the fibre therefrom. After a time, the carding bars should be cleaned to remove adhering flocks. For this purpose, they are movably supported, i. e. they are capable of rotating about the suspension trunnions *g* to place them in the cleaning position shown in dot and dash lines. The said bars are placed in the last

named position through the medium of the pivoted lever *h*, provided with a pawl *i* subjected to the influence of a spring *k* tending to keep the said pawl against an abutment *l* of the lever *h*. Each time the latter is operated, the pawl *i* engages the carding bars *e*, *e*₁, *e*₂, *e*₃ to place them in the cleaning position, and the said bars are subsequently brought back from the cleaning to the working position by the spring *n* (Fig. 2).

The lever *h*, pivoted at *m* may be operated by any member of the carding machine having a reciprocatory motion, for instance by the device for cleaning the travelling flats.

There are constructions of carding machines which do not allow the adaptation of the device in the form illustrated in Fig. 1, which in such cases must be suitably modified. One manner of modifying the same is illustrated by Fig. 3, wherein the carding bar *o* is at its ends formed in such a manner that it may slide within a slotted sector *p* of which the centre of the arc described by the slot coincides with the points of the teeth of the bar *o*.

I claim:

1. In carding machines, the combination with a breaker cylinder and breaker-bars under the said cylinder of movably supported toothed carding-bars arranged in the intervals between the breaker-bars, and means for oscillating the said carding-bars from a working to a cleaning position and reciprocally, substantially as described.

2. In carding machines, the combination with a breaker cylinder and breaker-bars under the said cylinder of movably supported toothed carding-bars arranged in the intervals between the breaker-bars, a pivoted lever fitted with a spring-pressed pawl adapted positively to engage the said carding-bars in one direction to oscillate them from a working to a cleaning position, and springs acting on the said carding bars and tending to return them to their working position.

In testimony whereof I have signed hereunto my name.

JOSEPH SCHMITT.
